W. W. LEWIS

DISPLAY RACK

Filed Feb. 26, 1925

UNITED STATES PATENT OFFICE.

WALTER W. LEWIS, OF SAN FRANCISCO, CALIFORNIA.

DISPLAY RACK.

Application filed February 26, 1925. Serial No. 11,780.

This invention relates to improvements in display racks and has particular reference to a display rack to be used in exhibiting garters, neck-ties, collars and the like.

5 The principal object of this invention is to produce a rack which is capable of securely maintaining the article being exhibited.

Another object is to produce a rack which 10 will accommodate itself to various sizes of articles.

Another object is to produce a rack upon which an article may be placed and later moved from place to place, without danger 15 of the article being deranged.

Other objects and advantages will be apparent during the course of the following description.

In the accompanying drawings forming a 20 part of this specification and in which like numerals are employed to designate like parts throughout the same,

Figure 1 is a front elevation of my improved rack, and

25 Figure 2 is a view similar to Figure 1, showing a garter positioned upon the rack.

I am aware of the fact that many forms 30 of display racks have been employed, but my rack comprises a resilient member over which an article to be displayed is draped and later secured under the hook positioned upon the main support. This three-point suspension of the article taken together with the resiliency of the arms serves to hold the 35 article being displayed in a much better manner than has been done heretofore.

In the accompanying drawings wherein 40 for the purpose of illustration is shown a preferred embodiment of my invention, the numeral 5 designates a base to which is detachably secured a standard 6 in the top of which is positioned a wire loop 7. This loop is common to various forms of display racks and serves the purpose of holding an advertising card or price tag thereon.

45 At 8 and 9 I have shown horizontal arms positioned on the standard 6, which arms are bent downwardly as shown at 11 and 12, re-

spectively and are further bent as shown at 13 and 14, respectively, so as to form hooks 50 upon the ends of the arms.

A hook 16 is secured as at 17 to the standard 6 and serves as the third point of suspension. In employing a display rack constructed in accordance with my invention, 55 the article to be displayed, for instance, a garter designated in Figure 2 by the numeral 18, is draped upon the arms 8 and 9, it, of course, being understood that the free ends of the garter are fastened together as is common practice in placing the garter around the leg. After being so draped over the arms 8 and 9 as to rest upon the bent ends 13 and 14, the hose-engaging portion 19 of the garter is grasped and pulled downwardly, that is, in a direction towards the base, with a result that the upper edge of the garter may be passed beneath the tip of the hook 16. 60

During this last mentioned operation the arms 8 and 9 will move from their full line 70 position of Figure 1 to the full line position of Figure 2, therefore, it will be noted that the tendency of these arms to straighten causes the garter to be tightly held beneath the hook 16 and over the bent ends 11 and 12 75 of the arms 8 and 9.

A neck-tie might be secured to my device in a similar manner. In employing a necktie the hook 16 would be concealed beneath one of the folds of the tie and therefore, the 80 tie would present a neat appearance. In displaying collars such as soft collars, the same will be draped upon the device and the hook 16 will be passed through the button-holes, with the result that the collar will present 85 an appearance similar to that when placed about the collar band of a shirt.

It will thus be seen that I have devised a display rack which will accommodate itself for use with many different articles. 90

It is to be understood that the form of my invention herewith shown and described is to be taken as a preferred example of the same, and that various changes in the shape, size and arrangement of parts may be resorted to 95 without departing from the spirit of the in-

vention or the scope of the subjoined claim. Having thus described my invention, I claim:—

In a display rack, a base, a standard vertically positioned on said base, resilient arms positioned on said standard, said arms extending horizontally outwardly therefrom, and in opposite directions to each other, said arms being bent downwardly and upwardly

so as to form hooked extensions, said hooked extensions serving to support and tension a garter or the like display thereon, and a retaining element positioned on said standard and serving to engage a portion of said garter for the purpose of displaying the same in a stretched position. ¹⁰ ¹⁵

In testimony whereof, I affix my signature. WALTER W. LEWIS.
